UNITED STATES PATENT OFFICE.

VINCENT BOVIO, OF FLUSHING, NEW YORK.

HAT AND PROCESS OF MAKING SAME.

1,303,246.

Specification of Letters Patent.

Patented May 13, 1919.

Application filed December 17, 1918. Serial No. 267,151.

To all whom it may concern:

Be it known that I, VINCENT Bovio, a subject of the King of Italy, having taken out his first U. S. naturalization papers, residing 5 at Flushing, L. I., N. Y., have invented certain new and useful Improvements in Hats and Processes of Making Same, of which the following is a clear, full, and exact description.

10 My invention relates to hats and to the process of making the same, and more particularly to straw hats, in which it is desired to produce a roughened, corrugated or undulatory effect in the finished hat, and the object of my invention is to provide an improved process for making such a hat, whereby the cost of production is greatly 15 lessened, and by which considerable variation may be made in the degree of roughened, corrugated or undulatory effect, which is given to the hat.

To the attainment of the above object, an important feature of my invention consists in forming a hat of fluted material, and more 20 particularly of fluted straw braid, which is sewed, or otherwise fastened together, to form a composite strip, which strip is fluted prior to being sewed together to form a complete hat.

25 Another important feature of my invention relates to the process whereby I can most conveniently control the degree of undulatory or corrugated effect, which is given to the hat, such process consisting in varying 30 the number of strands of braid which are formed into a composite strip, prior to fluting.

35 Other objects and important features of the invention will appear from the following 40 description and claims when taken in connection with the accompanying drawing, in which—

45 Figure 1 is a view of the complete hat made in accordance with my improved process.

Fig. 2 is a view showing a strip of straw comprising several strands of braid fastened together prior to being fluted.

50 Fig. 3 shows the composite strip of Fig. 2 after being fluted.

Fig. 4 shows the crown of the hat in the process of formation.

55 In order to produce a roughened, corrugated or undulatory effect in hats, it has been heretofore customary to so stitch each

individual piece of braid as to produce a slight tucking or gathering of the braid during the stitching operation, thereby producing the desired effect in the finished hat. The machines for producing this particular kind of stitching are quite expensive, and the degree of roughened or corrugated effect, which is produced on such machines, cannot be easily varied within wide limits.

My improved process overcomes the limitations imposed on the manufacture of hats by such machines, and furthermore enables me to produce a hat of very much improved appearance with very greatly lessened cost in labor and machinery.

In carrying out my process, I first stitch or otherwise fasten together, several strands of material out of which the hat is to be formed, such material being preferably straw braid, although it is of course understood that other suitable material may be used. This braid may be stitched together on an ordinary sewing machine, such as is well known and commonly used for this purpose. After several of these strands of braid have been stitched together in the manner set forth, of sufficient length to form a complete hat, the composite strip of braid is passed through ordinary fluting rollers. The strip of braid may be sized prior to being 70 passed through the fluting rollers, but this sizing is not, in any manner, necessary to the successful carrying out of my improved process. If, for instance, only two strands of braid are formed into a composite strip 75 and said strip is run through the fluting rollers, the fluting of such strip is quite pronounced; if three strips are run through the same or similar rollers under the same pressure, the fluting is less pronounced, the degree of fluting varying inversely with the 80 number of strands of which the composite strip is composed, a wide strip offering more resistance to the displacing action of the rollers than a narrow strip. In practice I 85 have found from three to five strands to be a convenient number to use in forming a composite strip.

After the strip has been fluted, it is stitched or otherwise formed into a complete 90 hat in the usual and well-known manner. After the hat has been completed, it may be sized, if so desired, although such sizing is not necessary to the carrying out of my improved process.

110

From the foregoing, it will be seen that I have produced an improved hat, and an improved process, whereby such hat is made, which process is susceptible of modification to produce wide variation in the appearance of the finished hat.

Having thus described my invention, what I desire to claim and secure by Letters Patent is:

- 10 1. The process of forming a hat which consists, in first fastening together a plurality of strips of material, fluting the composite strip of material thus formed and fastening together the composite strip of fluted material to form a hat.
- 15 2. The process of forming a hat which consists in, first fastening together a plurality of strips of straw braid, fluting the composite strip of braid thus formed and

fastening together the composite strip of fluted straw braid to form a hat.

3. The process of forming a hat having an undulatory effect, which consists in fastening together a plurality of strands of straw braid to form composite strips made up of varied numbers of strands, fluting the composite strips thus formed, the degree of fluting depending on the number of strands formed into each composite strip, selecting the composite strip having that degree of fluting which will give to the finished hat the desired undulatory effect, and fastening together the selected composite strip of fluted braid to form a hat.

Signed at New York this 16th day of December 1918.

VINCENT BOVIO.
